UNITED STATES PATENT OFFICE

LEWIS MOORE, OF JOLIET, ILLINOIS, ASSIGNOR TO MOORE BROTHERS COMPANY, OF JOLIET, ILLINOIS, A CORPORATION OF ILLINOIS

DESIGN FOR A KITCHEN RANGE

Application filed May 11, 1931. Serial No. 39,809. Term of patent 3½ years.

To all whom it may concern:

Be it known that I, LEWIS MOORE, a citizen of the United States, residing at Joliet, county of Will, and State of Illinois, have invented a new, original, and ornamental Design for Kitchen Range, of which the following is a specification, reference being had to the accompanying drawing, forming a part thereof:

The drawing is a perspective view of the design embodying my present invention.

I claim:

The ornamental design for a kitchen range as shown.

LEWIS MOORE.
